DESIGN FOR A FISH LURE

Howard F. Roessler, Philadelphia, Pa.

Application March 1, 1947, Serial No. 137,261

Term of patent 14 years

(Cl. D31—4)

To all whom it may concern:

Be it known that I, Howard F. Roessler, a citizen of the United States and a resident of Philadelphia, in the county of Philadelphia and State of Pennsylvania, have invented a new, original, and ornamental Design for a Fish Lure, of which the following is a specification, reference being had to the accompanying drawings, forming part thereof.

In the drawings, Fig. 1 is a perspective view; Fig. 2 is a top plan view; Fig. 3 is a side elevation and Fig. 4 is an end view of the leading end of a fish lure showing my new design.

I claim:

The ornamental design for a fish lure, as shown.
HOWARD F. ROESSLER.
